Lancaster, Allure & Ronne Attorneys

UNITED STATES PATENT OFFICE

151,560

DESIGN FOR A BELT

Dorris M. Scott and Evelyn Steinberg, Los Angeles, Calif., assignors to Anita-Gay Creations, Inc., Los Angeles, Calif., a corporation of California

Application February 26, 1947, Serial No. 137,174

Term of patent 14 years

(Cl. D3—10)

To all whom it may concern:

Be it known that we, Dorris M. Scott and Evelyn Steinberg, both citizens of the United States, residing at Los Angeles, in the county of Los Angeles and State of California, have invented a new, original, and ornamental Design for Belts, of which the following is a specification, reference being had to the accompanying drawing, forming part thereof.

Fig. 1 is a perspective view, looking toward the front of a belt, showing our new design.

Fig. 2 is a side elevational view of the same.

We claim:

The ornamental design for a belt, as shown.

DORRIS M. SCOTT.
EVELYN STEINBERG.
